SAW SWAGE.

No. 340,016.

Patented Apr. 13, 1886.

UNITED STATES PATENT OFFICE.

ALONZO STEVENS, OF WAUSAU, WISCONSIN.

SAW-SWAGE.

SPECIFICATION forming part of Letters Patent No. 340,016, dated April 13, 1836.

Application filed February 8, 1836. Serial No. 191,173. (No model.)

To all whom it may concern:

Be it known that I, ALONZO STEVENS, a citizen of the United States of America, residing at Wausau, in the county of Marathon and State of Wisconsin, have invented certain new and useful Improvements in Swages for Saw-Teeth, of which the following is a specification, reference being had therein to the accompanying drawings.

10 My invention is a saw-tooth swage, and, in brief, embraces the following novel features: A swage-frame, consisting of a pair of slightly-separated and bolt-clamped standard side plates having transversal and lever-turned fore-eccentric shaft, which reciprocally moves an intermedial half-block, conveying motion to a rectangular stamp-block, thus slid forward within a counterfacing slide-slots, cut horizontally across and into the inner faces of 15 said side plates, and held back against said shaft-eccentric by a counterpressing arm-spring, suitably secured against the front edge of one of said sides; also, said stamp-block having reversible and outwardly-inclining tooth-dies counter-projecting above and below the outer end of said block, and having, also, a strut-spring and screw-set tooth-gage, the fixed end of which is screwed against the basal edge of said block, while the plane top 20 of its gage-face correspondingly projects from the foot of the stamping-face of the said tooth-die above; also, a seven-sided or septagonal shaft-anvil, fittingly and transversely set into both said frame-sides and suitably in front 25 of said upper stamp-die; also, said eccentric-shaft having an incline-slotted cam-roller set-screwed upon the end opposite to that of its lever-arm, and conveying alternate motion to an overhanging clamp-lever through an angle 30 roller-pin arbored underneath the end of the long arm of said clamp-lever, and intermediately engaged by and engaging, respectively, said cam-roller and said clamp-lever; also, said clamp-lever issuitably pivoted between a pair 35 of horizontally-counterfacing bracket-hangers, and has an intermedial spring-block pressed against the inner curved face of its shorter arm, and provided with a freely-projecting push-pin extending from the inner end 40 of said spring-block to the inner face of the

frame-side, to which said bracket-hangers are secured; also, near the top of said frame sides are a pair of clamping set-screws, their flat points counterfacing inwardly toward each other through said sides; also, another clamping set-screw screwing inwardly and directly opposite to the pressing end of said spring-block push-pin; and, finally, in front of the lever-arm of said eccentric-shaft, and attached to that side of the swage-frame, is a segmentally-curved and correspondingly-slotted gage-plate, set-screwed to the curved plane of its vertical and rigidly-secured saddle-plate having a double pair of horizontally-projecting guide-studs, within which said gage-plate adjustably slides, all of which and their purposes are hereinafter more fully described, and illustrated by the accompanying drawings, in which like letters designate identical parts of my invention in the different figures respectively. 70

Figure 1 represents the front side of said swage-frame, showing the front end of the eccentric shaft and its lever-arm, the lever-arm throw-gage set-screwed upon its rigidly-secured saddle-plate, the saw-blade set-screws, 75 the front end of the septagonal anvil-die, and the front edge of the stamping-die return-spring. Fig. 2 is the rear side of said frame, showing the cam-roller on the rear end of the eccentric-shaft, the intermedial roller of the 80 long arm of the clamping-lever pivoted between its horizontal hanger-brackets, and the upper and counterfacing saw-blade clamping screw. Fig. 3 is the front end of said swage-frame, showing the front end of said stamp-block and four faces of its seven-sided shaft-anvil between the separated side plates of the swage-frame, the return-spring of said stamp-block on the front edge of the front side of 85 said frame, the upper pair of counterfacing clamping-screws, and the single set-screw counterfacing the clamping push-pin of the bracket-hung and eccentric-shaft roller and lever-clamp on the rear side of said frame, and the front edges of the lever-arm gage-plate and its rigidly-secured saddle-plate. Fig. 4 is the inner face of the rear side of said frame, showing the eccentric and the intermedial half-block, into which it engages upon 90 each side of the transversal motor-shaft, the 100

sliding stamp-block, with its reversible tooth-die and return-arm spring, the transversal shaft-anvil and the saw-blade-clamping push-pin above it, and the hands of the clamping-lever bracket-screws, together with the point-face of one of said pair of upper clamping-set-screws. Fig. 5 is the inner face of the front side of said frame, showing the cam-roller end of said eccentric-shaft, together with the return-spring and anvil-die of said stamp-block and the point-faces of the clamping set-screws above; and Fig. 6 is the rear end of said swage-frame, showing the rear view of all of the aforesaid swaging devices, together with the separative screw-blocks between the frame sides.

The object of said invention is to provide a saw-tooth swage having a gripping and clamping mechanism for holding the tooth to be swaged, which shall automatically clamp the tooth with any desired pressure before the swaging begins, hold it without increase of pressure until the desired extent of swaging has been completed, and then release the saw sufficiently to swage another tooth or to allow it to be entirely withdrawn.

The letter A represents the said swage-frame, the side plates, B, of which are suitably separated, with sufficient space between to properly support and operate the inclosed stamping mechanism by the blocks a, through which the bolts or screws pass to clamp and hold said sides firmly and evenly opposite to each other, as shown.

C is the said eccentric-shaft, which is supported within suitable bearing-holes made transversely and oppositely through said frame-sides, as shown, and suitably turned by a very strong and powerful lever-arm placed and set-screwed upon the front and squared end of said shaft. The eccentric b, made on the middle of said shaft, so as to work between the frame-sides, as shown, has but little throw, in order that its fore-eccentric motion shall have great and safe power; and it engages within the fitting concave of the intermedial half-box, c, which has a free and horizontally-reciprocal movement with the eccentric, in order to convey said motion with the utmost directness and power to the said stamp-block d, which thereby is forcibly slid forward between said frame-sides within counterfacing slot or cleat grooves e, horizontally and correspondingly cut across the inner faces of both said frame-sides, as shown, said stamp-block being made to return to its normal position, closely following the reverse movement of said eccentric, by the angle-arm of the return-spring f, screwed to the front edge of one side of said frame, as shown. The stamp-block d has the pair of said tooth-stamping dies g rigidly formed or fixed upon its rectangularly-faced outer end and projecting by suitably-inclined faces to an angle-edge above and below said block end, as shown, in order to present a proper stamping or pressing face against the back of the saw-tooth

clamped and ready to be swaged in said frame. Said stamp-dies are also made interchangeable, and by simply reversing the top and bottom edges of said block d allow a worn or damaged one above to be replaced by the sound one below, thus doubling the usefulness of the die-block. The anvil or stationary die D is a seven-sided and septagonal shaft, and firmly set in corresponding and closely-fitting bearings, made transversely and horizontally through both said frame-sides, as shown, so that the two lower rear faces of said shaft-anvil will fit the gullet of the said clamped saw-tooth, being suitably fixed in front of the stamp-face of the movable die, will properly resist the pressure of the said shaft-eccentric, thereby to swage the interposed tooth into the desired form. In order to prevent the overspread of the said interposed tooth end below the bottom of the stamp-die face, and cause the tooth-metal to run evenly sidewise instead, during the swaging process, thus properly broadening the point of the tooth, the strut-spring tooth-gage h is provided and foot-screwed against the bottom edge of said stamp-block d, said spring-gage being made to closely fit over the angles and edges of said block and lower die, and having a horizontal plane face on the top of its vertical arm, as shown. The depth to which the said saw-teeth are to be severally inserted between said stamp-die and anvil is regulated also by the said tooth-gage set-screw s, the flat point of which is screwed horizontally through the vertical arm of the spring-gage against the front end of the stamp-block, as shown, thereby regulatively extending the depth of the inclined face of the stamp-die, and consequently the length of the swaged tooth. The anvil-die can be readily taken out and replaced in its bearings with any one of its shaft-faces suitably opposite the stamp-face of said movable die, so that should one of its angular shaft-edges crumble or become otherwise useless another angle-edge with its adjacent faces can be readily replaced without furnishing a new anvil-die. The said several set-screws for the purpose of suitably adjusting and holding the saw-blades, whether rip or crosscut, in the swage-frame before the clamping mechanism is moved, are the pair of flat-pointed ones i, oppositely placed near the top of the frame, and the single one, j, screwing through the front frame-side with its point-face brought directly opposite that of said clamping push-pin, as shown.

The clamping mechanism, as shown, consists substantially of said cam-roller E, suitably fixed upon the rear end of said eccentric-shaft C, for the purpose of engaging, whenever said shaft is turned forward by its power-lever L, the outwardly-moved angle-roller k, which, being rolled upon the spiral incline of said cam-roller, conveys alternate motion to the clamping-lever l, which, being vertically pivoted near its front or clamping end within said

bracket-hangers *m*, converts said lever-motion into a steady but powerful pressure, through said intermediate spring-block, *n*, upon the said clamping push-pin *p*, which firmly clamps the unswaged saw-tooth, adjusted, as aforesaid, upon the shaft-anvil and between the frame-sides, against the counterfacing set-screw *j*, which clamping process is simultaneously automatic with the fore-eccentric throw of said stamp-die against the anvil-die, and when the return motion of said eccentric is made, followed by said back-springing stamp-die, the clamping-pressure upon said swaged tooth is also automatically withdrawn, and said swaging process upon said saw-tooth has been accomplished. The extent of the pitch of the lever of said shaft *C* and the sequent throw of its fore-eccentric *b* are regulatively limited by the said lever gage *G*, the center of the segmental curve of which coincides with that of said eccentric-shaft, and which is set-screwed upon its saddle-plate *v*, vertically secured against the outer face of the front side of said swage-frame, as shown. The cross-beam (shown in the top and front of said swage frame of the drawings) is to be discretionally used to simply support the structure against any sidewise pressure when in use; therefore,

What I claim as new, and desire to secure by Letters Patent, is—

1. In the swage-frame consisting of a pair of slightly-separated and bolt-clamped standard-plates, the transversal turn-shaft having power lever and intermediate fore-eccentric, in combination with the horizontally-moved and vertically-reversible stamp-block having the intervening eccentric-block, interchangeable stamp dies, return-motion arm-spring, and screw-set tooth-gage, and with the transversal shaft-anvil having several sides and included angle-edges, all made and adjusted as herein described, to simultaneously and automatically co-operate with the adjunctive clamping appa-

ratus adjustably attached upon and in the rear standard side of said swage-frame, and consisting of the cam-roller adjusted upon the rear end of said eccentric-shaft and having the spiral incline in its outer and engaging face, the engaged roller of the horizontally-bracketed clamping lever, and its return springing push-pin inwardly projecting through said rear frame-side toward the set screw counterpointing through the front frame side, all substantially as and for the purposes herein specified. 45

2. In the swage-frame herein described, the combination, with the fore-eccentric-transversal turn shaft, of the reversible stamp-block, horizontally slid in counterfacing and supporting slot-grooves in the inner faces of the separated frame-sides, and having the intervening eccentric block, interchangeable stamp-dies, returning arm-spring, and counter-springing screw-set tooth-gage, and of the stamp-block transversal shaft-anvil having several interchangeable sides and angle-edges, 65 substantially as and for the purposes herein specified. 6c

3. In the swage-frame containing the saw-tooth swaging portion of the machine herein described, the combination, with the said fore-eccentric swaging-shaft, of the said adjunctive saw-clamping portion, consisting of the said shaft-coupling and automatically-engaging cam-roller, the vertically-pivoted and horizontally bracket-hung clamping-lever having at 75 the end of its long arm the power-connective friction-roller, and at the curved end of its clamping short arm the return springing push-pin, substantially as and for the purposes herein specified. 70 80

In testimony whereof I affix my signature in presence of two witnesses.
